(57) **CLAIM**

The ornamental design for a hinged shower door as shown and described.

DESCRIPTION

FIG. 1 is a front elevational view of a hinged shower door showing my new design;

FIG. 2 is a rear elevational view thereof;

FIG. 3 is a perspective view thereof;

FIG. 4 is a second perspective view thereof;

FIG. 5 is an enlarged view of portion 5 shown in FIG. 3;

FIG. 6 is an enlarged view of portion 6 shown in FIG. 3;

FIG. 7 is an enlarged view of portion 7 shown in FIG. 3;

FIG. 8 is an enlarged view of portion 8 shown in FIG. 3;

FIG. 9 is an enlarged view of portion 9 shown in FIG. 3;

FIG. 10 is an enlarged view of portion 10 shown in FIG. 4;

FIG. 11 is an enlarged view of portion 11 shown in FIG. 4;

FIG. 12 is an enlarged view of portion 12 shown in FIG. 4;

FIG. 13 is an enlarged view of portion 13 shown in FIG. 4;

FIG. 14 is an enlarged view of portion 14 shown in FIG. 4;

and,

FIG. 15 is an enlarged view of portion 15 shown in FIG. 1.

The dash-dash lines in the drawings show portions of the hinged shower door that form no part of the claimed design. The dot-dash broken lines in FIGS. 1, 3-15 showing boundaries of the enlargement areas form no part of the claimed design.
